UNITED STATES PATENT OFFICE.

JOHN A. McMANUS, JR., OF LYNN, MASSACHUSETTS.

CASTING-MACHINE.

1,015,818.

Specification of Letters Patent. Patented Jan. 30, 1912.

Application filed October 28, 1908. Serial No. 459,864.

To all whom it may concern:

Be it known that I, JOHN A. McMANUS, Jr., a citizen of the United States, residing at Lynn, county of Essex, State of Massachusetts, have invented certain new and useful Improvements in Casting-Machines, of which the following is a specification.

The object of the present invention is to provide a casting machine which is especially applicable to the casting of inlays, bridges, etc., for dental work, but it is realized that the same principles may be adopted to advantage in the construction of larger machines, and machines requiring greater energy consumption, for other purposes, such as the casting of jewelry, etc.; requiring only the adaptation of mechanical skill to the utilization of the principles herein involved.

Another object of the invention is to provide an apparatus of such a construction that it will effectively heat the material of which the casting or inlay is to be made, and at the same time heat the mold to the most favorable degree for carrying out the casting operation.

In the case of one type of machine with which I am familiar, which machine has been designed for the casting of gold inlays, the gold is first deposited in a receptacle in juxtaposition to a mold of the desired shape, the said receptacle communicating with the mold by a suitable sprue hole. The receptacle and mold are carried by an arm which is revolved by means of a clock-spring in the base of the machine. After the gold has been deposited in the receptacle it is heated to the desired state by playing upon it a flame such as an oxy-hydrogen blow flame. The gold after being thus heated is then transferred into the mold by means of the centrifugal force developed by the revolving arm. Of course, in this case the flame has to be taken off before the carrier is started revolving. It will be seen, therefore, that the mold has to attain its heat at the same time that the gold in the receptacle is being heated, and the mold is not heated to an amount where it will appreciably assist in the casting operation.

By means of my improved apparatus an electrical means is provided by virtue of which a continuous and at the same time, a uniform heat slowly increasing in temperature is applied to both the casting material

contained in the receptacle and also to the mold itself. The uniformity of heat distribution and gradual increase of temperature thus obtained minimizes the liability of distortion of the shape and size of the mold. This is accomplished as the result of the employment of an electrically heated crucible having a negative temperature coefficient; such material as carbon, for instance, in which case the heating is gradual, or slow and even, because the initial resistance is high but gradually falls off as the temperature increases, assuming constant potential.

The device which is provided by my invention is one that can readily be attached to an ordinary electrical circuit used in commercial practice, that is, one in which a transformer can be connected for use with the machine, and such a circuit is usually available in dental offices, laboratories, and the like. The machine also enables one or several inlays or bridges to be cast at one time, according to the requirements of the operator. The same receptacle and flask that is used for the casting of inlays can be used in the casting of bridges, the flask which contains the mold being of such a size as to accommodate the bridge. In case it is desired not to use certain flasks, the metal covers of these particular flasks are taken off, and thus the path for the electric current is interrupted at these points.

My invention will be better understood by reference to the accompanying drawings which are merely illustrative of certain of the forms in which my invention may be embodied, and in which—

Figure 1 is a vertical section taken on the line 1—1 of Fig. 2. Fig. 2 is a plan view of the device shown in Fig. 1. Fig. 3 is a plan view of one of the heating units and flasks employed in my improved apparatus; Fig. 4 is a vertical section taken on the line 4—4 of Fig. 3; Fig. 5 is a similar section showing the operation of casting a dental bridge; Fig. 6 illustrates a tooth provided with an inlay cast by means of my improved apparatus; Fig. 7 illustrates a natural tooth and an artificial tooth bridged together by means of a bridge also cast by my improved device, and Fig. 8 illustrates diagrammatically the electrical connections employed for starting the motor by means of a thermostat after the gold in the receptacles has attained a certain predetermined temperature.

1 represents the base of the device of my invention. Either fastened to or cast integral with this base is a standard 2. Formed in the upper and lower portions of this 5 standard are ball-bearing races 3 and 4 respectively containing ball bearings 5 and 6. Mounted so as to revolve on these ball-bearings is a hub-like member 7 having at its top, and integral therewith, a flanged portion or carrier 8. Mounted upon the revolving member 7 are slip-rings 9 and 10, or what are commonly known as collector rings. The carrier 8 has mounted thereon one or 10 several molds, as desired. In this case I have shown several molds represented by 15 11, 12, 13, 14, etc., communicating by means of sprue holes 15 with receptacles 16. These receptacles may be composed of any material which will best suit the particular case where 20 the resistance should be such as to furnish heat enough by the passage of an electric current through them to bring the gold or other material in the receptacles 16 to the proper state for casting. In the embodiment 25 of the invention herein disclosed I have shown carbon as the resistance material, but any other refractory material which will satisfactorily meet the conditions is within the scope of my invention. The copper conducting ring 17 extends around the lower 30 inside faces of the carbon receptacles and thus serves to convey current from the conducting wire 30 to the receptacles and thence to the molds.

35 Referring now to the electrical connections of the device herein illustrated and described, 18 and 19 represent brush holder studs upon which are mounted the brushes 20 and 21. These brushes convey current to 40 and from the collector rings 9 and 10 respectively. The brush holder studs are mounted in holes 22 in the base 1 and are suitably electrically insulated from said base, such as by the insulating washers 23 and 24.

45 Nuts 25 on the studs hold the latter in place, and also serve to hold the terminal clips 26 of the conductors 27 and 28. The conductors 27 and 28 are led through insulating bushings 29 in the base 1, to the studs 18 and 19.

50 A flat copper conducting wire 30 conveys current from the collector ring 9 through the copper conducting ring 17 to the various receptacles and flasks. A copper conducting strip 31 extends circumferentially around 55 the tops of the flasks on the carrier 8 and in electrical connection with said flasks, thus forming a path for the return circuit for the electric current. Connected with this metal conducting strip 31 and with the collector ring 10 is another copper conducting strip 32 similar to the one represented by 30. The mold 11 best illustrated in Figs. 4 and 5 is in communication with the receptacle 16 by means of the sprue hole 15. The mold 60 may be made of any material suitable for

such purpose known to the art, such as wax, and is embedded in the investment material 33 which may be any standard investment material found in the dental market. The mold, of course, is formed to the desired shape by first making a wax impression, say of the cavity in the tooth to be filled if the work in hand is an inlay, and of the shape of the mouth in proximity to the gums, if for a bridge. This wax cast is then embedded 70 in the investment material, boiled out and absorbed by the investment material, and when the gold is heated to the proper temperature it is forced by centrifugal force to occupy the space formerly occupied by the wax. When the gold is cooled, an inlay or bridge of the desired shape is the result. The flask 34' of metal is insulated by insulating material 34 of high electrical and heat insulating qualities, capable of withstanding extremely high temperatures; such a material for instance as asbestos board, now on the market. This insulating material 34 is made so as to receive the carbon receptacle and the mold, in such manner as 80 to effectually insulate them from the metal carrier 8. The flask 34 is inserted in place in the carrier 8, the latter being made of metal and so shaped or tapered as to form a holding means for the flask. Each flask 90 is provided with a steel cover 35, and it is upon these steel covers and also upon the posts 36 that the conducting strip 31 rests, the said conducting strips, of course, being suitably insulated from these posts, as by 95 insulating washers. The steel cover 35 and the cover 35' of the receptacle 16 may be taken off in one piece as the two are held together by means of the steel screw-threaded pin 37, upon the end of which is a 100 knob 38 made preferably of heat non-conducting material. The pins 39 which are provided with thumb-nuts 40 serve to fasten down the cover to the flask 34'. While I have mentioned the pins 37 and 39 as being made 105 of steel, they may be made of any material which will withstand the high temperatures to which they are subjected. Extending through the steel cover 35 and forming a 110 communicating passage between the mold 115 and the outer atmosphere is a passage 41. This passage 41 affords a vent for the gases from the mold. When it is desired to take off the cover, the thumb-nuts 40 are unscrewed which removes the pins 39. The 120 cover can then be pulled out from under the conducting strip 31 by means of knob 38.

Referring now to the construction shown in Fig. 5, it is essentially the same as that shown in Fig. 3, only that a bridge mold is 125 shown in the flask instead of an inlay. 42 represents a porcelain facing such as is ordinarily employed for artificial teeth, extending from which are the usual platinum pins 43. A gold backing 44 is placed next

the porcelain facing 42, the pins 43 extending through said backing. This backing piece 44 is to prevent the hot gold from the receptacle 16 from cracking the porcelain facing which it is likely to do if the hot gold is allowed to come in direct contact with the facing. When the gold from the receptacle 16 flows into the mold 11' it is fused to the backing piece 44, around the platinum pins 43 and forms the bridge 45 to the shape of the mold. The bridge may either be cast integral with a gold crown 46, Fig. 7, which fits over the natural tooth, or the portion 45 alone may be cast in the mold. If the latter method is employed the bridge piece 45 can, when finished and taken out of the flask, be fused to a gold band swaged around the natural tooth to which the bridge is to be fastened.

The operation of my invention is as follows: The material to be fused, and of which the casting is to be made, is first placed in the receptacle 16. The current is then turned on by the closing of the main switch 47. This controls the current of the main circuit which flows through the receptacle and heats the gold. After the gold has attained the required temperature, the carrier 8 is started revolving, either by starting up by hand an auxiliary motor operatively connected with the pulley 48, Fig. 1; or the machine can be started automatically by means of a thermostat in heat conductive relation with the heating receptacle, and so arranged as to automatically close at a predetermined temperature a switch in the circuit of the motor connected to the pulley 48. Of course, if it is decided to dispense with this mechanism, it is a simple enough matter to start up by hand the electric motor or other source of power belted or otherwise connected with the casting machine. In this case, however, it will be necessary to exercise vigilance to see that the gold or casting material has attained the desired temperature before starting the power, whereas if this operation is performed automatically the mechanism can be adjusted to act at the desired moment. The automatic thermostatic regulation is accomplished in the manner illustrated in Fig. 8 in which 11 and 16 represent the mold and receptacle respectively connected in circuit with the mains 50 and 51. 49 represents the casting machine also connected to the mains 50 and 51 by the conductors 27 and 28 leading to the taps 52 and 53 taken from the mains. The conductors 30 and 32 lead from the collector rings of the casting machine to the conducting strips 17 and 31. Taps 54 and 55 are taken off of the conductors 30 and 32 thus forming a shunt to the main circuit. In this shunt circuit is the thermostat 56 and the magnet coil 57. The thermostat 56 as has been previously stated, is in heat conductive relation with the heating receptacle. The contacting members 58 and 59 of this thermostat are normally separated and are electrically insulated from each other by the insulating block 60. The thermostat 56 is composed of two members, each member in turn comprising two different metallic pieces 61, 61' and 62, 62', the particular metals being chosen which afford the most desirable thermal couple, such as cast iron and aluminum. By having the proper arrangement of these metals as to their coefficients of expansion the thermostat members may be bowed inward or outward upon being subjected to high temperatures. In this case I have chosen to have them bow inward in order that the contacts 58 and 59 may complete the shunt circuit in which is the motor 63, for operating the casting machine. In order to accomplish this result in this case, therefore, if cast iron and aluminum are chosen as the desirable metals for the thermal couple, the aluminum members will be on the outside and the cast iron on the inside. The closing of the contacts 58 and 59 completes the shunt circuit in which also is the magnet coil 57. When this magnet coil becomes energized by the closing of the contacts 58 and 59, the end 64 of the pivoted switch 65 is attracted to the magnet and the end 66 of said switch closes the contacts 67 and 68, thereby starting the motor 63, as the latter is connected by the conductors 52 and 53 with the mains 50 and 51. The motor 63 is belted or geared to the casting machine and thus operates the same, causing the gold to be forced into the molds by centrifugal force. When the magnet coil 57 is deenergized the end 64 of the switch 65 drops with the assistance of the spring 69, and thus opens the motor circuit, shutting off the motor 63. The temperature at which the thermostat acts can be regulated by adjusting the screw 70 either inward or outward, thus causing the thermostat to act at a higher or a lower temperature, as desired.

I will now describe the path of the current through the machine: Starting with the current entering the conductor 27, the current flows to the brush holder stud 18, through the brush 20 to the collector ring 9, through the conducting strip 30, conducting ring 17 to the carbon receptacle 16, thence through the steel cover 35, copper conducting ring 31, conducting strip 32, collector ring 10, brush 21, brush holder stud 19 and out through the conductor 28. The resistance of the receptacles 16, and the various electrical proportions of the conductors, etc., are so designed as to produce a degree of heat in the receptacle sufficient to fuse the gold shortly after the current has been turned on. This gold or material of which the casting is to be made is forced

through the sprue hole 15 into the mold 11, due to the action of the centrifugal force developed by the revolving carrier 8; and the pressure thus exerted upon the material in the receptacle can be regulated by varying the rate of speed of the revolving member. When this operation of casting is completed, the current is turned off by turning off the switch 47, the power is stopped and the machine is allowed to cool down, when the mold can be taken out and the cast removed from it. If the cast is an inlay it can then be cemented into place in the cavity of the tooth. This is illustrated in Fig. 6, where 15 in 71 represents the inlay cemented into place in the tooth 72.

My invention may be embodied in many other forms than that shown and described, and I therefore do not wish to be restricted 20 to the exact forms shown, but intend to cover by the appended claims all changes and modifications within the spirit and scope of my invention.

What I claim and desire to secure by Letters Patent of the United States, is:

1. In a casting machine, the combination of a receptacle for the casting material, a suitably shaped mold, means for heating the receptacle, and means automatically set into 30 operation after the material in the receptacle has attained a predetermined temperature for transferring said material from the receptacle into the mold.

2. In a casting machine, the combination of a receptacle for the casting material, a suitably shaped mold to receive said material, electrical means for initially fusing the material in the receptacle and maintaining the material fused during the casting operation, and means for transferring the material from the receptacle into the mold after 40 it has attained the desired temperature.

3. In a casting machine, the combination of a receptacle for the casting material, a suitably shaped mold, electrical means for heating the receptacle and the mold, a stationary member, a revolving member supported thereby, and means dependent upon the centrifugal force developed by the revolving member for causing the material in the receptacle to be forced into the mold.

4. In a casting machine, the combination of a receptacle containing casting material, a mold for receiving the material, centrifugal means acting on the material while in the receptacle for forcing the material from the latter into the mold, and means for continuously heating the mold and the receptacle during the casting operation.

5. In a machine for casting inlays, the combination of a receptacle, a suitably shaped mold for receiving material from the receptacle, electrical means for slowly and evenly heating the mold and the receptacle, and centrifugal means for forcing the ma-

terial from the receptacle into the mold after it has attained the proper state.

6. In a machine for casting inlays, the combination of a receptacle for casting material, a suitably shaped mold, a stationary member and a revolving member, comprising means by virtue of which the material is forced from the receptacle into the mold, and conductors conveying current from a source of supply to the receptacle and mold for heating both. 75

7. In a machine for casting inlays, a plurality of receptacles for casting material, a corresponding plurality of molds for receiving the material, means for forcing said material from the receptacles into the molds, and means for heating the material in order to fuse it said means comprising conductors conveying electric current from a source of current supply to the receptacles and molds. 80

8. In a machine of the character described, the combination of a rotating member, a plurality of metal containing receptacles and molds radially arranged upon said member, electrical means for heating all of the molds 90 and receptacles comprising means for conveying current to and from the receptacles and molds, and means for rotating the receptacles and molds to permit the metal to flow from the former to the latter under the action of centrifugal force.

9. In a machine for making castings, a revolving carrier, a suitably shaped mold carried by said carrier, a receptacle also carried by the carrier for containing the material of 100 which the casting is to be made, means for heating the material in the receptacle to the proper state for casting comprising conductors leading from a source of current supply to and from the receptacle and mold, and means for forcing the material from the receptacle into the mold.

10. In a machine for making castings, a carrier, a plurality of molds mounted on said carrier, a plurality of receptacles for the 110 casting material also mounted on said carrier, communicating means between each of said receptacles and its corresponding mold, electrical means for heating each and all of said receptacles and molds, and means for revolving the carrier so as to force the material from the receptacles into the molds under the action of centrifugal force when the said material has attained the proper state. 115

11. In a machine for making dental castings, the combination of a carrier, a plurality of molds and receptacles mounted on said carrier, communicating means between each receptacle and its corresponding mold, 125 electrical means for heating to the proper state the material of which the castings are to be made, and centrifugal means for forcing the material from the receptacles into the molds when it has reached that state. 130

12. In a machine for making dental castings, the combination of a carrier, a plurality of receptacles and molds radially arranged on said carrier, electrical means for heating the receptacles and molds, means for cutting out of operation one or several of the receptacles and molds as desired, and means for forcing the material contained in the receptacles into the molds by centrifugal action.
13. In a machine for making castings, the combination of a rotary carrier, a mold in which a dental bridge may be cast mounted upon said carrier, a metal containing receptacle communicating with said mold, electrical means for continuously heating the receptacle and the mold, and means dependent upon the centrifugal action developed by revolving the carrier for forcing the metal from the receptacle into the mold when the said metal has attained the proper state.
14. In a machine of the character described, the combination of a rotary carrier, a driving means therefor, receptacles for the material of which the casts are to be made mounted on said carrier, molds in communication with said receptacles also mounted on the carrier, means for heating the receptacles and molds, and a device for automatically starting the driving means into operation when the casting material has attained the desired temperature.
15. In a machine of the character described, the combination of a rotary carrier, a driving means therefor, receptacles for the material of which the casts are to be made mounted on said carrier, molds in communication with said receptacles also mounted on the carrier, means for heating the casting material to a high temperature, and a thermostatic device for automatically starting the driving means into operation after the casting material has become fused.
16. In a machine of the character described, the combination of a rotary carrier, receptacles for the material of which the casts are to be made mounted on said carrier, molds in communication with said receptacles also mounted on the carrier, electrical means for heating said receptacles and molds, a driving motor, a switch in the motor circuit, and a thermostat which operates to close the switch and start the motor after the material in the receptacles has become fused.
17. In a casting machine, the combination of a receptacle for the casting material, a suitably shaped mold, means for heating the receptacle, a stationary member, a revolving member supported thereby, and means dependent upon the centrifugal force developed by the revolving member for causing the material in the receptacle to be forced into the mold.
18. In a casting machine, the combination of a receptacle and a mold for casting material both simultaneously rotatable, with means for heating the casting material in two stages, the first stage while the machine is stationary to melt the casting material in the receptacle and the second during the transfer of the melted material from the receptacle to the mold under the centrifugal force developed by the movement of the receptacle and mold.
19. In a casting machine, the combination of a receptacle and a mold for casting material mounted to rotate together with means for heating both the receptacle and mold to continuously heat said material both prior to and during the casting operation.
20. The combination of a rotatable electrical furnace, a mold movable therewith, and means for operating the furnace and mold for forcing molten material from the furnace into the mold.
21. The combination of a rotatable furnace continuously operating while in motion with a mold arranged to receive molten material from the furnace while the latter is in motion.
22. In a casting machine, the combination of a receptacle for the casting material, a suitably shaped mold, a single means for simultaneously heating the receptacle and mold, and means for transferring the material from the receptacle into the mold.
23. In a casting machine, the combination of a receptacle for casting material, a suitably shaped mold, means for heating the receptacle, and means controlled by the temperature for causing the material to be transferred from the receptacle into the mold.
24. In a casting machine, the combination of a receptacle for the casting material, a suitably shaped mold, means for heating both the receptacle and mold, and means controlled by the temperature for causing the material to be automatically transferred from the receptacle into the mold after said material has attained a predetermined temperature.

In witness whereof, I have hereunto set my hand this twenty-sixth day of October 1908.

JOHN A. McMANUS, JR.
